(57) **CLAIM**

The ornamental design for a supporting material of ink container for ink cartridge, as shown and described.

DESCRIPTION

FIG. 1 is a perspective view of the front, right side and top plan of a supporting material of ink container for ink cartridge showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is a perspective reference view of the front, right side and top plan showing the usage thereof.

The elements shown in broken lines are for illustrative purposes only and form no part of the claimed design.
